UNITED STATES PATENT OFFICE.

ROBERT P. BARNSTEAD, OF ASHMONT, MASSACHUSETTS.

STERILIZER.

SPECIFICATION forming part of Letters Patent No. 742,560, dated October 27, 1903.

Application filed August 1, 1902. Serial No. 117,975. (No model.)

To all whom it may concern:

Be it known that I, ROBERT P. BARNSTEAD, a citizen of the United States, and a resident of Ashmont, in the county of Suffolk, State 5 of Massachusetts, have invented certain new and useful Improvements in Sterilizers, of which the following is a full, clear, and exact description.

This invention relates to sterilizers of the 10 type in which an air-tight drum is employed for receiving the articles to be treated and the sterilizing heat is obtained by means of coils of steam-pipes.

My invention has for its object, first, the 15 effecting of improved means whereby the process may include a moist heat for a portion of the time, followed by a dry heat accompanied with a current of hot air; second, the construction of a door for said drum 20 which shall be easily and conveniently opened and closed, and yet perfectly tight when closed and safe against any powerful internal pressure, and, third, certain details of improvement hereinafter set forth.

25 Referring to the drawings forming part of this specification, Figure 1 is a side elevation, partially in section, of my complete apparatus. Fig. 2 is a front elevation of the same with the door partially open. Fig. 3 is a detail sectional view upon nearly full scale of one of the door-fastening devices. Fig. 4 is a side view upon a smaller scale of the front end of the drum, showing its door closed.

As shown in Fig. 1, the drum 1 is preferably constructed with two concentric shells 35 2 and 3, containing between them the helical coils of steam-piping 9, with suitable asbestos packing between said coils and the outer shell to prevent radiation and loss of heat.

40 On the floor of this drum is formed, by means of the segmental front 4, a water-container having a roof 5, perforated at frequent intervals, as at 6. Within this container are several lengths of piping 7, having their ends 45 terminating outside the drum, as at 8 8, and there connected with a suitable source of steam-supply. This container is drained at its rear end by a pipe 10, closed by a suitable valve, as the lever throttle-valve 11 illustrated. Through the roof of this drum at its 50 front end is a pipe 12, closed by a similar lever throttle-valve 13.

In using this sterilizer the articles to be

treated are supported upon the perforated container-roof 5, which is more truly the 55 floor of the drum, and the door tightly closed. Previously water has been introduced within said container until the steam-pipes 7 are properly covered. The valves 11 and 13 being closed, steam is turned onto the coils 9 60 and pipes 7, and the sterilizing process thereby begun. The water in the container soon becomes hot, so that heat is being emitted from the floor 5 equally with that from the walls of the drum. In a short time the water 65 in said container begins to boil and steam to rise therefrom, passing through the perforations 6 and filling the entire drum. Any excess of pressure from the heated air and this accumulating steam is allowed to escape 70 through the pop-valve 16, held down by the weight 17, and the diminution of the water is evidenced by the water-glass 15, connected with the pipe 10, more being supplied through the tubing 14. When this moist heat has continued for a sufficient length of time, the valve 11 is opened to permit the water to escape, a suitable receptacle 19 being provided therefor, and then both valves 10 and 13 are allowed to remain wide open, the steam mean- 75 time being continued in the coils 9 and piping 7. Through said pipes 10 12 the outside air now begins to pass, the same as it rises from the pipe 10 being obliged to circulate between the piping 7 before escaping through 80 the perforations 6, and hence being thoroughly heated and rendered asceptic before entering the drum itself. Being thus heated it seeks to rise, and so passes on up and out through the pipe 12. In this manner a con- 85 tinuous circulation of hot dry air is maintained until the final step in the process of sterilization is accomplished and all the moisture contained in the articles has been fully removed. Before opening the valve 11 the 90 valve 13 should be opened to remove pressure that would throw water from pipe 10 with undue force.

My improved door for the drum is constructed as follows: This door 20 is pivoted 95 at 21 to swing in its own plane, a handle 22 being provided for its manipulation. Fixed to the drum a few inches in front of the said door is the ring 27, the fastening devices for said ring comprising the bolts 28. These 100 bolts are shown as four in number, although

any suitable number may be employed, the essential point being that they shall be located in one half of the ring alone and that by preference the left-hand half, as shown in Fig. 2.

5 The ring 27 being thus supported the door 20 can be swung unhindered to the right and downward until it hangs vertically down from its pivot 21.

The fastening devices for the door consist 10 of the hand-screws 30, which turn and slide freely in suitable holes in the ring 27 and are tapped into the annular head 25 of the drum at their inner ends. The diameter of the door is made less than the outer diameter of said 15 ring, so that the hand-screws 30 shall be exterior thereto, as shown in Fig. 3, when the door is closed. Fixed on each hand-screw 30 is a shoulder 32 of a sufficient diameter to overlap the edge of the door, whereby the 20 latter may be pressed firmly against the drum annulus or head 25 or with its flange 23 embedded in the comparatively soft packing-ring 26, set into the head 25. For reducing friction said shoulders 32 may be provided 25 with balls 33, held in an annular groove in the face of the shoulder.

As shown in Fig. 3, the ring 27 is far enough from the door to permit the latter to clear the ends of the hand-screws 30 when these have 30 been unscrewed and pulled out until the shoulders 32 contact with said ring. When this has been done, said door is free to be swung away from the mouth of the drum.

Inasmuch as the door only swings to one 35 side, owing to the presence of the supporting-bolts 28, it is only necessary to thus remove the hand-screws in the right-hand side of the ring 27, the balance being simply unloosened enough to free the door. For the other hand-screws, those which require to be wholly withdrawn from the path of the door, I provide 40 each with a coiled spring 35, fitting between the hand-wheel 31 of the screw and the ring 27 and so constructed that as soon as the 45 screw-threads of a hand-screw 30 have emerged from the head 25 such spring will instantly throw the hand-screw out of the path of the door and retain it there so long as desired. Without such springs care is needed to wholly 50 withdraw the hand-screws when the door is to be opened, and also during the operation of filling and emptying the drum of the articles being treated one or more of such hand-screws are liable to be hit, and thereby moved 55 back into the path of the door, so that when the door is quickly swung up into place it would be sure to strike such displaced hand-screw and so bend it or mar its screw-threads 60 as to oblige the entire arrangement to be removed for repairs.

As shown in Fig. 2, I prefer to surround the upper end of the pipe 12 with a cup 18 to catch whatever moisture may issue therefrom with the air passing up from the drum.

What I claim as my invention, and for 65 which I desire Letters Patent, is as follows, to wit:

1. The combination of a chamber having an opening, a door fitted to said opening and constructed to swing away therefrom in its 70 own plane, fastening devices for securing said door to the chamber constructed to be wholly disengaged from the door, and means located exterior to said door and out of its path when opened and closed, for supporting 75 said fastening devices in position to be immediately engaged with the chamber.

2. The combination of a chamber having an opening, a door fitted to said opening and constructed to swing away therefrom in its 80 own plane, a ring located exterior to said door and fixed to said chamber at certain parts thereof, and fastening devices loosely supported by said ring and constructed to be engaged with said chamber and door. 85

3. The combination with the drum and its door pivoted to swing in its own plane, of the ring fixed a short distance exterior to the open mouth of the drum, and a series of hand-screws revoluble and slidable in said ring 90 and terminally tapped into the end of said drum and each being formed with a shoulder for engaging the edges of the door, substantially as described.

4. The combination with the drum and its 95 door pivoted to swing in its own plane, of the ring, bolts holding said ring a short distance exterior to the open end of the drum, and a series of hand-screws revoluble and slidable in said ring and terminally tapped into the 100 end of the drum and formed with the shoulders engaging the edges of the door, substantially as described.

5. The combination with the drum and its door pivoted to swing in its own plane, of the 105 ring one half of which is rigidly connected to the drum, the hand-screws revoluble and slidable in the ring and terminally tapped into the end of the drum and having the shoulders engaging the edges of the door, 110 and spiral springs located with certain of the hand-screws exterior to the ring to throw the same away from the drum as soon as unscrewed therefrom, substantially as described.

6. The combination with the drum and its 115 door pivoted to swing in its own plane, of the shouldered hand-screws for fastening the door in place, said shoulders being formed with annular grooves, and antifriction-balls located in said grooves, substantially as described.

In testimony that I claim the foregoing invention I have hereunto set my hand this 30th day of July, 1902.

ROBERT P. BARNSTEAD.
